WIRE DRAWING AND COILING MACHINE

Carroll E. Orr, Orange, N. J., assignor to Syncro
Machine Company, Rahway, N. J., a corpora-
tion of New Jersey

Application April 14, 1942, Serial No. 438,877

3 Claims. (Cl. 205—16)

This invention relates to improvements in wire drawing and coiling machines, but as it will appear from the following description, the subject matter of this invention is not specifically limited to use in such a combination.

The general object of this invention is to provide as part of a wire drawing and coiling or spooling machine, automatically operating mechanism for disconnecting the coiler or spooler from its power drive and braking it quickly to a stop when the wire going to the wire drawing machine from its supply source becomes tangled and locked. This combination is so arranged and timed that the coiler or spooler block will be brought to a stop before the supply wire is broken.

Further and more specific objects of this invention and the details of accomplishing it in one form of mechanism will be set forth herein-after in full detail in connection with the attached drawings.

This invention resides substantially in the combination, construction, arrangement and relative location of parts, as will be described in detail below.

In the accompanying drawings,

Figure 1 is a side elevational view of a wire drawing and coiling machine showing the subject matter with this invention applied thereto;

Figure 2 is a top plan view of the same mechanism;

Figure 3 is a right hand end elevational view thereof;

Figure 4 is an enlarged detailed view, partly in central cross section, of the mechanism for holding the clutch and brake operating member, in operating position;

Figure 5 is an enlarged side elevational view of one of the control switches;

Figure 6 is a horizontal cross-sectional view through the right hand end of the machine showing the clutch and brake structure; and

Figure 7 is an enlarged cross-sectional broken view of the clutch and brake mechanism.

One of the important problems in the handling of wire in the various methods of processing it, as for example in drawing it and where the wire is taken from a supply coil or spool, it frequently happens that the wire becomes tangled or kinked or locked between the point of supply and the wire drawing machine. It is common practice to provide some form of mechanism controlled by the wire for insuring a sufficient supply of wire after a kink or locking occurs to feed the processing machine, as for example the wire

drawing machine, during the period it is being automatically brought to a stop, so as not to cause breakage of the wire, as the result of its locking due to the tangle or kink therein. In one form of practice, an extremely long arm is pivotally supported in the path of movement of the wire from the supply reel to the machine, having a guide pulley thereon over which the wire passes, and which acts to form a long bight in the wire. This bight insures an adequate supply of wire, after locking or kinking occurs, to feed the machine during stopping. In such an arrangement the formation of the kink or tangle or the occurrence of locking will stop the supply of wire from the supply reel, thereby pulling the long arm downwardly. The initial movement of this arm operates control devices to bring the machine to a stop, and while it is stopping the arm continues to descend under the pull of the wire so as to supply from the long bight enough wire so that it will not be broken before the machine comes to a stop. There are other forms of mechanisms for accomplishing a similar purpose, as for example a pulley system which forms loops in the wire which decrease in size during the stopping period to supply sufficient wire to prevent breakage. In many situations both of these arrangements have disadvantages.

The object of this invention is to provide a substitute mechanism for combinations of this type, likewise having the function of supplying sufficient wire during stopping of the machine without breakage. The general principle of this invention is to employ a buffer arm like that previously described, but one which may be much shorter, which arm is pulled downwardly when the wire tangles and locks and operates a switch a device for disconnecting the coiler or spooler block from its power drive, and, immediately, applying a brake thereto to quickly bring it to a stop. A result is that the buffer arm may be much shorter, because less wire is required due to the fact that the block comes to a stop so quickly. As soon as the coiling block comes to a stop the tension which it exerts on the wire between it and the delivery end of the drawing motion of course drops off to zero with the result that the wire drawing machine even though it continues to run will not demand or pull any more wire from the source in view of the fact that slippage occurs between the wire and the drawing drums. It is because of this inherent function of the wire drawing machine that it is possible to disconnect the coil block from its drive

and brake it so quickly to a stop because of its relatively lighter mass that it is possible to prevent the breakage of wire due to locking or kinking with a much smaller bight in the wire than is the case with prior art arrangements. If desired, and as disclosed, this same or an additional switch may be employed to de-energize the power drive of the wire drawing machine so that it too will come to a stop.

A particular advantage of the novel combination disclosed is that by braking the block to a stop a much smaller braking arrangement may be used than would be required to brake the whole machine to a stop. Furthermore, when braking the whole machine to a stop the braking action is detrimental to the drive motor and to the machine itself.

The manner of operation of a wire drawing machine is such that even though it does not come to a stop in synchronism with the coiler block no harm to the drawing machine or to the wire in it will result because, as is known in the art, the machine only supplies wire as it is demanded by the coiler block. It is apparent, therefore, that it is not necessary to brake the driving motor of the wire drawing machine to a stop in synchronism with the block or even to stop the motor if the complication of automatic control is undesirable for some reason.

Before describing the embodiment herein disclosed it may be noted, as will be appreciated by those skilled in the art, that the principles of this invention may be applied to other wire processing machines. The description herein as applied to a wire drawing machine, is not, therefore, supplied in a limiting, but rather in an illustrative sense.

Referring to the drawings there is illustrated in Figures 1, 2 and 3, a combined wire drawing and coiling machine as indicated by the reference numeral 1. The wire drawing portion of the machine is generally indicated by the reference numeral 2 and the coiler block is shown at 3. The wire W is supplied from any suitable supply source such as a coil, reel or spool, to a pair of guide wheels 4 from which it passes to and around the guide pulley 5. The pulley 5 is rotatably mounted on the buffer arm 6 which is secured to a shaft 7 journaled on the side of the machine, as is clear from Figure 2. The buffer arm 6, in accordance with this invention, is much shorter than the one commonly used. The outer end of shaft 7 has a weighted arm 7' mounted thereon which tends to hold the arm 6 in the raised position shown in Figure 1.

The wire passes from the pulley 5 around a guide pulley 8 which is rotatably mounted on a yoke 9 which is adjustably attached to a suitably shaped bracket 10 on the side of the machine. Thus the guide pulley 8 may be properly positioned to feed the wire into the entering end of the wire drawing machine. A switch 13 of suitable construction is mounted on the side of the machine and is provided with an operating lever 12 positioned to engage an operating member 11 adjustably mounted on the buffer arm 6. The switch 13 is shown in greater detail in Figure 5. It consists of an oscillatable contact blade 85 within the switch housing mounted on a shaft to which the operating arm 12 is secured. Mounted within the housing are a pair of contacts 80 and 81 positioned to be engaged by the contact 85 when the arm 12 drops in a counterclockwise direction. When the buffer arm is in raised position as shown in Figure 1, switch 13 will be open.

The wire W passes into the drawing portion 2 and extends back and forth from the rotatable drawing blocks DB passing successively through reducing dies (not shown), in accordance with usual practice.

The finishing die 14 is mounted at the point of exit of the wire from the drawing machine and positioned so as to feed the wire onto the coiler or spooler block 3 which is rotatably mounted on a vertical axis. The operating motor 15 for the machine is mounted thereon as shown in Figure 2. The block 3 is rotated from some suitable point in the wire drawing machine by means of a belt or chain 16 which extends to a pulley or sprocket 17 mounted on the horizontal shaft 18 journaled in the right hand end of the machine housing.

Referring to Figure 7, the structure mounted on the shaft 18 comprises the clutch and brake as shown in detail. The sprocket 17 is integral with the rotatable housing 30 of a disc clutch within which housing are the clutch discs 35. The housing 30 has a series of grooves 30' into which radial lugs on the peripheries of the discs 35 project. Thus discs 35 can slide axially but they rotate with the housing 30 on shaft 18. Interleaved with the clutch discs 35 are the cooperating clutch discs 35' which are similarly keyed to a sleeve 32 with which they rotate, but on which they have axial movement. A ring clamp comprises rings 34" and 34 which are threaded together and are free to rotate and slide on the sleeve 32. The sleeve 32 is secured to the shaft 18 by means of a key 33. One annular face of the ring 34" is inclined as indicated at 34'. At 36 is an annular housing secured to the machine frame and having mounted therein a series of disc clutch elements 31 having peripheral lugs lying in the grooves 36'. These clutch elements are interleaved with cooperating clutch disc elements 39 which are keyed to the sleeve 32 but which can also slide on the sleeve. A ring clamp comprising the connected rings 38" and 38 is freely slideable and rotatable on sleeve 32. A ring 38" is provided with an annular inclined face 38'. Between the annular faces 34' and 38' is a sleeve 41 integral with the sleeve 32. The clutch operating ring 20 surrounds this sleeve and has an outer peripheral groove in which the fingers of the oscillatable yoke 21' ride. It is to be noted that there is no particular novelty in the disc clutch and disc brake per se.

Referring back to Figure 6 it will be seen that the yoke 21' is mounted on a shaft 27 which extends out of the housing and has secured on its end a weighted lever or operating arm 28. Journaled in the housing parallel to shaft 18 is another shaft 23 and these two shafts are connected by the gears 21 and 22. Shaft 23 is provided with a bevel pinion 24 meshing with a bevel gear 25 which is mounted on a vertical shaft 26 which extends above the machine and to which the block 3 is secured.

The lever 28 rides in a guideway formed by the latch housing 29 and the guide rods 29' mounted thereon, as clearly shown in Figure 4. The hooked end of the angle lever 100 is positioned so as to normally engage the lever 28 and thereby hold it in raised position. The lever 100 is pivotally supported at 100'. A pin 105 on lever 100 engages a slot in the yoke 103' which is connected by the link 103 to the plunger 102 of a solenoid 83. A spring 104 surrounds the link 103 between the yoke 103' and a fixed bracket to hold these connected parts in the position shown in Figure 4.

The winding 83 of the solenoid is connected to the circuit wire 84 and to one of the terminals of switch 83''. Wire 84, as is clear from Figure 1, is one of the current supply wires, while the other supply wire 82 is connected to the other terminal of the switch 83'' and to one terminal of switch 13. The other terminal of switch 13 is connected to the operating windings 83^a of a relay, of which switch 83'' is a part. Winding 83^a is also connected to wire 84. Switch 83' is a part of the relay which controls a circuit for the main driving motor 15.

Returning to Figure 7, it will be seen that the sleeve 41 has cut out portions in which are pivotally mounted the clamping cams 40 and 42 respectively. Cam 40 is shown in clamping position, which position it takes when lever 28 is in the position shown in the various figures, and at which time solenoid winding 83 is de-energized. At this time yoke 27' is in the position shown in Figure 7 and has forced the clamping cam 40 against the inclined face 34' of the ring 34'' so as to move it to the right and cause the two sets of discs of the clutch to firmly engage, and therefore lock the driving sprocket 17 to the shaft 18. When the yoke 27' is shifted to its other position the ring 20 releases the clamping cam 40 and engages the clamping cam 42, which acting through the camming face 38' causes the clutch elements 37 and 39 to engage and provide a braking action on the shaft 18, thus quickly bringing it to a stop. At the time the brake comes into operation the clutch is released so that shaft 18 is free of its power source.

While the above description may be adequate for a full understanding of the machine, a little additional description may be desirable. When the machine is operating, weighted lever 28 is in the position shown and is held there by the end of lever 100. The buffer arm 6 is in raised position and switch 13 is open. The clutch is engaged so that when the main motor is energized, switch 83^a being closed, the wire drawing machine will operate and the block 3 will revolve. Power for this purpose is supplied from the wire drawing machine through the connection 16 to the sprocket 17 which is now clutched to the shaft 18. Thus shaft 23 is driven through the gears 21 and 22, and shaft 26 in turn is driven through the gears 24 and 25. Thus the block 3 is revolving and coiling the wire upon it. Should the wire tangle or kink, or for any reason stop feeding, the tension therein will increase and arm 6 will be swung downwardly. As soon as it begins to move, switch 13 closes, energizing winding 83^a so that switch 83^a opens and switch 83'' closes. The opening of the former de-energizes the control circuit for motor 15 and the closing of the latter energizes solenoid 83. Lever 100 swings against the resistance of spring 104 in a counterclockwise direction through the action of the plunger 102. The end of the lever 100 disengages the weighted arm 28, which is free to move in a clockwise direction (Figure 3). This causes shaft 27 to revolve, carrying with it yoke 27' so that the operating member 20 disengages the clutch and applies the brake in the manner previously described. Hence the block 3 will quickly come to rest and before the wire W has straightened out

the bight formed by the buffer arm 6, so that the wire will not break. The main or drawing portion of the machine coasts to a stop at the same time.

From the above description it will be apparent to those skilled in the art that many detailed modifications can be made of the invention herein disclosed without departure from the novel subject matter thereof. I prefer, therefore, to be limited by the scope of the claims granted me, rather than by the illustrative description herein given.

What is claimed is:

1. The combination with a motor driven wire drawing machine, of means for supplying wire thereto, a pivotally supported arm positioned to form a bight in the wire between the supply and the machine, means for holding said arm in bight forming position, the tightening of the wire due to kinking or locking swinging said arm to bight releasing position, a switch positioned to be held open by said arm in bight forming position, a rotatable coiling device positioned to receive wire from said drawing machine, power means for driving said coiling device from said drawing machine including a clutch, a brake for said coiling device only, means for disengaging the clutch and applying the brake, and means connected to said switch for actuating said clutch and brake actuating means, whereby the bight formed by said arm supplies sufficient wire while said coiling device comes to a stop to prevent breakage of the wire due to kinking thereof.

2. The combination with a power driven wire drawing machine of means for supplying wire thereto, movable means for forming a bight in the wire between the supply and the machine, means for normally holding said bight forming means in bight forming position, the tightening of the wire moving said bight forming means in a direction to gradually decrease the size of the bight, a switch operated by the movement of said bight forming means, a rotatable coiling device positioned to receive wire from said drawing machine, power means for driving said coiling device including a clutch, a brake for said coiling device, means for disengaging said clutch and applying said brake, and means connected to said switch for actuating said clutch and brake actuating means whereby the bight formed by said bight forming means supplies sufficient wire while said coiling device comes to a stop upon operation of said switch to prevent breakage of the wire.

3. The combination with a wire processing machine and means for supplying wire thereto, of a movable support for forming a bight in the wire between the supply and the machine, a rotatable coiling device arranged to receive wire from said machine, a power means, a clutch for connecting said power means to said coiling device to cause it to revolve, a brake for said coiling device, and means controlled by said movable means for disengaging the clutch and applying the brake when the tension in the wire increases to cause said movable means to move, the wire in said bight being sufficient to supply said machine during the stopping of said coiling device.

CARROLL E. ORR.
